US0D1007825S

(12) **United States Design Patent** (10) **Patent No.:** **US D1,007,825 S**
(45) **Date of Patent:** **** Dec. 19, 2023**

(54) **FOOTWEAR**

(71) Applicant: **Mountain Origins Design LLC**,
Jackson, WY (US)

(72) Inventors: **Kurtis Tamotsu Sakai**, Santa Barbara,
CA (US); **Stephen Sullivan**, Wilson,
WY (US); **Kelly Hill Shuptrine**,
Jackson, WY (US)

(73) Assignee: **Mountain Origins Design LLC**,
Jackson, WY (US)

(**) Term: **15 Years**

(21) Appl. No.: **29/831,915**

(22) Filed: **Mar. 23, 2022**

(51) LOC (14) Cl. **02-04**

(52) U.S. Cl.

USPC **D2/969**; D2/970

(58) **Field of Classification Search**

USPC D2/896, 900, 902, 904, 906-908,

D2/916-924, 925-945, 947-960, 969-979

(57) **CLAIM**

The ornamental design for footwear, as shown and described.

DESCRIPTION

FIG. 1 is a perspective view of a novel footwear design.

FIG. 2 is a front view of the novel footwear design in FIG. 1.

FIG. 3 is a rear view of the novel footwear design in FIG. 1.

FIG. 4 is a left side view of the novel footwear design in FIG. 1.

FIG. 5 is a right side view of the novel footwear design in FIG. 1.

FIG. 6 is a top view of the novel footwear design in FIG. 1; and,

FIG. 7 is a bottom view of the novel footwear design in FIG. 1.

The broken lines are shown for illustration purposes only and form no part of the claimed design.

1 Claim, 5 Drawing Sheets
